UNITED STATES PATENT OFFICE.

ALBERT NITKA, OF SOBIESKI, WISCONSIN.

CURTAIN-POLE.

1,079,431.

Specification of Letters Patent. Patented Nov. 25, 1913.

Application filed June 17, 1912. Serial No. 704,155.

To all whom it may concern:

Be it known that I, ALBERT NITKA, a subject of the Emperor of Austria-Hungary, residing at Sobieski, in the county of Oconto 5 and State of Wisconsin, have invented certain new and useful Improvements in Curtain-Poles, of which the following is a specification, reference being had therein to the accompanying drawing.

- 10 This invention relates to curtain poles, and the objects of my invention are, first, to obviate the necessity of using rings and pins for retaining the upper ends of curtains in engagement with a pole; second, to 15 provide a metallic curtain pole that is inexpensive to manufacture, neat in appearance and highly efficient for the purposes for which it is intended; third, to provide a metallic curtain pole that can be easily rolled 20 and pressed from sheet metal, and fourth, to provide a curtain pole that can be supported by inexpensive brackets.

I attain the above objects by a mechanical construction that will be hereinafter specifically described and then claimed, and reference will now be had to the drawing, wherein:—

Figure 1 is a perspective view of a portion of a pole in accordance with this invention, Fig. 2 is a cross sectional view of the same. Fig. 3 is an end view of a clamping member, and Fig. 4 is a similar view of a modified form of member.

A curtain pole in accordance with this invention comprises a hollow tubular shell 1 having angularly disposed flanges 2 extending from one end of the shell to the opposite end thereof, said flanges providing a longitudinal V-shaped groove 3.

- 40 Extending into the groove 3 is a longitudinal V-shaped clamping member 4 that has the longitudinal edges thereof provided with flanges 5. The clamping member 4 is of less length than the shell 1, and the upper 45 ends of curtains 6 are placed between said member and the walls of the groove 3 to be frictionally held by said member. To retain

the clamping member 4 in the groove 3, split bands 7 are arranged upon the shell 1, adjacent to the ends thereof. 50

The bottom of the shell 1 is provided with openings 8 and these openings receive the outer ends 9 of screw brackets 10 said brackets being mounted in the frame or support in connection with which the curtain 55 pole is to be used. The brackets 10 extend upwardly between the flanges 2 at the ends of the member 4.

The upper ends of the curtains 6 after having been clamped by the member 4 can 60 be suitably draped, whereby the curtains will present a neat appearance in connection with the pole.

What I claim is:—

A curtain pole comprising a split cylindrical shell having the longitudinal edges thereof spaced from each other and each terminating in a depending longitudinally disposed inclined flange, said shell having its bottom formed with openings, said flanges 70 projecting toward each other and forming a V-shaped groove at the top of the shell, a longitudinally extending V-shaped clamping member arranged within said groove and provided at its top with oppositely disposed 75 clamping flanges overlapping the longitudinal edges of the shell, said member adapted to retain the upper end of a curtain against said inclined flanges, the supporting means for the shell having vertical portions extending upwardly through said openings and between the lower edges of the inclined flanges and at the ends of said member, and annular clamping bands mounted upon the shell for maintaining said member in said 80 groove and for clamping the curtain to the front thereof. 85

In testimony whereof I affix my signature in the presence of two witnesses.

ALBERT NITKA.
